UNITED STATES PATENT OFFICE

166,035

CHILD'S ROCKING CHAIR

Bertis F. Hamilton, Columbus, Ind.

Application December 11, 1950, Serial No. 13,368

Term of patent 14 years

(Cl. D15—6)

To all whom it may concern:

Be it known that I, Bertis F. Hamilton, a citizen of the United States, residing at Columbus, Bartholomew County, Indiana, have invented a new, original, and ornamental Design for a Child's Rocking Chair, of which the following is a specification, reference being had to the accompanying drawing, forming part thereof.

Figs. 1 and 2 are side and front elevations respectively of a child's rocking chair embodying my new design, and Fig. 3 is a plan view thereof.

I claim:

The ornamental design for a child's rocking chair, as shown.

BERTIS F. HAMILTON.
